UNITED STATES PATENT OFFICE.

FRANK K. BERRY, OF CALHOUN, MICHIGAN, ASSIGNOR TO A-B-STOVE COMPANY, OF BATTLE CREEK, MICHIGAN, A CORPORATION OF MICHIGAN.

WATER-HEATER.

1,246,848.

Specification of Letters Patent. Patented Nov. 20, 1917.

Application filed May 17, 1915. Serial No. 28,545.

To all whom it may concern:

Be it known that I, FRANK K. BERRY, a citizen of the United States of America, residing at Battle Creek, in the county of Calhoun and State of Michigan, have invented certain new and useful Improvements in Water-Heaters, of which the following is a specification, reference being had therein to the accompanying drawings.

10 It is the object of the invention to obtain a simple and inexpensive construction of water heater, which may be used as a substitute for the so-called instantaneous heaters in which the water is heated only as required for immediate consumption. It is usual with this type of heater to control the gas automatically by the valve or tap through which the hot water is drawn. This, however, requires a relatively large amount 20 of heating surface, so that the water may be brought to the proper temperature while it is flowing through the pipe, and further a large consumption of gas is also required to quickly generate the necessary heat.

25 With my improvement I employ a relatively small heating coil, and with the consumption of a moderate amount of gas I am enabled to heat the water as required, controlling the heat from the point of consumption.

30 In the drawings:

Figure 1 is a diagram, showing my improved heater and the control mechanism therefor; and

35 Fig. 2 is a section through the controlling valve.

A is the heater, which is provided with a coil B connected with the water system and leading to a tap C. D is the gas burner for 40 heating the coil A, and E is the gas supply pipe controlled by a valve F. F' is a pilot light supplied with gas from the conduit below the valve and having its discharge end arranged in proximity to the gas burner for 45 lighting the same.

In place of controlling the valve F by the faucet or tap C, I arrange in convenient proximity thereto an operating handle G for actuating a flexible pulley connection H. 50 This connection passes over suitable pulleys I I', and is attached to the stem J of the valve. The valve is operated by a spring K for automatically actuating the same to closed position, the arrangement being such 55 that whenever the pulley of the connection

is released the valve will close, but by operating the handle G the valve may be opened.

With the construction as described in use, whenever the operator wishes a supply of 60 hot water, it is only necessary to move the handle G from its normal position to a position where it exerts a pull upon the connection H. This will open the valve F, permitting a supply of gas to the burner D, 65 which is automatically lighted from the pilot F'. The burner D is of annular form and is so constructed that the flame therefrom will envelop the coils, quickly elevating the temperature of the water contained 70 therein, after which the tap C may be opened and the hot water drawn off. It is also possible to open the gas and water valves differentially, so that the temperature of the discharged water may be varied as desired. 75 In case of the breakage of the control handle G or connection H, the spring K will automatically close the valve, thereby avoiding waste of the fuel.

Any suitable construction of the valve F 80 may be employed, but I prefer that of a slideable gate L having the spring K sleeved upon the stem J thereof, so that the direct pull of the connection H will be exerted upon the valve and the direct pressure of 85 the spring will return the same. The gate in closing enters a pocket L in the casing, in which a small quantity of gas is trapped, and a vent passage M connecting this pocket with the outlet permits of the displacement 90 of said trapped gas. This construction is useful in preventing the popping out of the burner or the slight explosion occurring when the gas is suddenly cut off and which might result in the blowing out of the pilot 95 light. The gas which is trapped in the pocket and slowly expelled therefrom through the passage M will prevent the sudden cutting off of the supply and will thereby avoid the explosion.

100 What I claim as my invention is—

1. In a water heater, the combination with a heating coil, a tap located at a remote point therefrom and a connection between said coil and tap, of a gas burner, a valve 105 for controlling the supply of gas to said burner, comprising a gate longitudinally movable from closed to open position, a spring for normally closing said gate, a casing having a pocket into which said gate is 110

pressed in the closed position of the valve, said pocket having a vent connection to the gas outlet passage, and a pull connection extending from said valve to a point in proximity to said point, permitting control of the gas valve independently of the water connections.

2. In a water heater, the combination with a heating coil, of a tap located at a remote point therefrom, a connection between said coil and tap, a gas burner for heating said coil, a pilot light adjacent said gas burner, a valve for controlling the supply of gas to

said burner, means for actuating said valve from a point adjacent said tap, said valve 15 having a pocket in which gas is trapped in the closed position of the valve, and having a vent from said pocket to said gas outlet passage.

In testimony whereof I affix my signature 20 in presence of two witnesses.

FRANK R. BERRY.
